Donald E. Windle Attorneys.

UNITED STATES PATENT OFFICE

2,115,274

SUPPORTING BASE

Viola McCabe, Miami, Fla.

Application December 6, 1935, Serial No. 53,184

3 Claims. (Cl. 248—194)

One of the objects of my invention is the provision of a portable supporting base which may be used as a weighted base or as a clamping base.

Another object of the invention is the provision of a base which is compact, which requires a minimum of space while in use, and which is easily and quickly converted from one type of base to the other.

A further object of the invention is the provision of a base having arm members for adjustably supporting a magnifying glass, electric light socket and bulb, or other like article.

Still another object of the invention is the provision of a new article of manufacture which is simple of construction, which is economical to manufacture, and which may be sold to the public at a nominal cost.

Other objects and advantages of my invention will suggest themselves in the course of the following description, and that which is new will be correlated in the appended claims.

The most satisfactory manner of carrying out the principles of my invention in a practical, economical, comprehensive, and efficient manner is shown in the accompanying one sheet of drawings, in which:

Figure 1 is a side elevation of the invention, the same illustrating its use as a weighted base.

Figure 2 is a plan view of the invention, taken from line 2—2 of Figure 1.

Figure 3 is a front elevation of the base, taken from line 3—3 of Figure 1.

Figure 4 is a side elevation of the base, the same being used as a clamping base in connection with a solid-top table or the like.

Figure 5 is a side elevation of the base indicating the same in connection with a table or other similar support having downwardly extending flanges therearound.

Figure 6 is an isometric detail view of the main body member of the base.

Figure 7 is an isometric detail view of the clamping member of the base.

Figure 8 is an isometric view of the base in partially assembled condition.

Similar indices designate like parts throughout the several views.

In order that the construction and the advantages of my invention may be more fully understood and appreciated, I will now take up a detailed description thereof, in which I will set forth the same as fully and as comprehensively as I may.

1 A designates a table or other supporting surface upon which the base is adapted to rest.

designates the main body member, the same being preferably formed of metal, or of other suitable material. 1' designates the inverted L-shaped notch or groove which is formed in the rear side of the main body member 1 and extends the full length thereof, the same extends forwardly and thence downwardly, and forms a space for a companion portion of the clamping member 2. 1'' designates a rearwardly extending channel which is formed the full length of the front side and extends rearwardly therefrom and forming a space for the reception of the hinged member 4. 1^a designates a comparatively smaller and upwardly extending channel formed in the upper surface of the channel 1'', the same being formed the full length of the main body member 1 and provides a space for the reception of the hinge member 3 of the clamping member 2, as shown in Figure 8.

2 designates the main portion of the clamping member, the same forming a surface upon which the base rests when the same is assembled as shown in Figures 1, 2, and 3. The main portion 2 has the upwardly extending leg 2' formed integrally therewith and at the rear edge thereof with the upwardly extending portion 2'' terminating in a forwardly extending portion 2''' and which is adapted to slide endwise into the upper portion of the inverted L-shaped groove 1' of the main body member 1, as shown in Figure 8. The main portion 2 also has the leg 2^a formed integrally with the forward edge thereof, the same being formed at right angles to the main portion 2 and extends upwardly therefrom. The hinge member 3 extends the full length of the portion 2^a and has one leaf thereof rigidly secured thereto in any well-known manner. 4 designates the spacing block which is rigidly secured to the free leaf of the hinge 3 in any well-known manner. The spacing block 4 extends the full length of the member 2, as shown in Figure 7. The upwardly extending leg 2^a has the raised portion 2^b formed integrally with the front face thereof, the same having a threaded aperture formed therethrough for the reception of 45 the threaded screw 5 which is adapted to bear, at its inner end, against the spacing block 4.

6 designates the upwardly extending arm which is formed integrally, at its lower end, with the upper portion of the main body member 1, the same having an aperture formed through its upper end for the reception of the threaded tension screw 7. 8 designates a second arm member which is adjustably secured, at its lower end, to the upper end of the arm member 6 by means of 55

the threaded adjusting screw 1, said adjusting screw having a head portion 1' formed on one end thereof with the threaded nut 9 removably secured on the opposite end thereof, and which 5 provides means for adjustably clamping the members 6 and 8 together at the ends thereof.

10 designates a clamping member which is adapted to clamp around the handle portion of a magnifying glass or the like, the same having 10 one end of the adjusting screw 11 rigidly secured in one side thereof with the opposite end thereof being threaded and projecting through an aperture formed through the upper end of the arm member 8 with the threaded nut 12 adjustably securing the same therethrough. 13 15 designates the handle portion of a magnifying glass, 14 designates a rim which surrounds the glass 15.

When it is desired to use my supporting base 20 as a weighted base, the member 2 is slipped endwise onto the lower side of the main body member 1, as shown in Figure 8, with the upwardly extending leg 2' and the forwardly extending portion 2'' registering with the inverted L-shaped 25 groove, and with the spacing block 4 and the hinge 3 registering with the channels 1'' and 1^a respectively of the main body member 1, after which the threaded screw 5 is turned, thereby forcing the spacing block 4 rigidly against the 30 body member 1.

When it is desired to clamp the base onto the edge of a table or the like, the threaded screw 5 is loosened, and the clamping member 2 is slipped endwise off of the main body member 1. The 35 portion 2' and 2'' of the member 2 is inserted into the inverted L-shaped groove 1' of the main body member 1. When the base is to be clamped in connection with a table or the like not having downwardly extending flanges formed there- 40 around, the spacing block 4 is swung away from the portion 2^a, as shown in Figure 4, and the threaded screw is turned inwardly until the same sets firmly against the under side of the 45 table or object to which it is secured. When the table has downwardly extending flanges formed around the edges thereof, the spacing block 4 is positioned as shown in Figure 5, and the threaded screw 5 is tightened thereagainst, there- 50 by rigidly securing the base to the table.

It will be noted that the design of the base and the associated parts thereof are for the most part, of square design, but I desire that it be understood that minor changes may be made in the several details, and in the arrangement of the parts herein shown and described without departing from the spirit of the invention or sacrificing any of the advantages thereof.

Having now fully shown and described the invention, what I claim and desire to secure by Letters Patent of the United States, is:

1. In a supporting base, a main body member having grooves formed in two opposite sides thereof, a clamping member having legs formed thereon, said legs being adapted to register with 15 the grooves formed in the main body member, with said clamping member being adapted to slide endwise onto the main body member by means of the legs of the clamping member registering with the grooves of the main body mem- 20 ber, and means for securing said clamping mem- 25 ber in fixed relation with said main body mem- 30 ber.

2. A supporting base comprising in combina- 25 tion, a main body member having an L-shaped groove formed in one side thereof, a clamping member having an L-shaped projection formed integrally with one side thereof, with the L- shaped projection of the clamping member being adapted to register with the L-shaped groove of 30 the main body member, and means securing the clamping member in removable relation with the main body member.

3. A supporting base comprising a rectangular 35 block member having an L-shaped groove ex- 40 tending through one end and a channel extend- 45 ing through the opposite end and a clamping member including a body having upstanding end 50 portions at two opposite ends thereof, one of said upstanding portions being L-shaped and the other having a block hinged to its upper part and also having a screw extending therethrough and adapted to engage said hinged block where- 55 by when the L-shaped upstanding portion is dis- 60 posed in the L-shaped groove and the hinged block is disposed in the channel the hinged block 65 may be moved to clamp the rectangular block member and the clamping member rigidly to- 70 gether.
